UNITED STATES PATENT OFFICE

IVON S. PIETERS, OF CHICAGO, ILLINOIS, ASSIGNOR TO PLIBRICO JOINTLESS FIRE-
BRICK COMPANY, OF CHICAGO, ILLINOIS, A CORPORATION OF ILLINOIS

ANCHOR FOR FURNACE LINING

Application filed July 21, 1926. Serial No. 123,825.

This invention relates to anchors, more particularly to anchors for anchoring or tying a lining or facing to a wall.

The invention has to do especially with anchoring plastic fire-brick or refractory linings to the structural brick walls of furnaces, and the like, and its objects are the provision of an anchor which will permit contraction and expansion of the lining in drying and 10 firing the same, without injuring the lining or producing undesirable stresses therein, and the provision of an anchor that may be economically produced and conveniently handled and installed.

15 The invention is illustrated in the accompanying drawings, in which:—

Figure 1 is a perspective view, partially in section, of an anchor embodying the present invention; and

20 Figure 2 is a fragmentary section showing a plastic refractory lining or facing as tied to the structural brick wall of a furnace with the anchor of the present invention.

The anchor assembly comprises two parts, 25 both of which may be made up of strap steel which may be cut from scrap pieces. The part 10 comprises a base 11 having two upturned ends 12 and 13. As will be noted from Figure 2, the ends are preferably made long 30 enough to partially surround a brick, but any convenient or desired proportions may be used. The part 14 comprises a base 15 having a relatively long upturned end 16, and a relatively short upturned end 17. A slot 18, 35 forming an eye of just sufficient width to easily accommodate the end or finger 13 of the part 10, is formed as by stamping out a lip 19 from the base 15, and in applying the part 14 to the part 10 it is simply slipped over the tongue 13 which extends upwardly 40 through the opening or slot 18. The slot 18 is longer than the width of the upturned end 13 of the part 10, as shown in Figure 1, this difference permitting side play or relative 45 motion of translation between these parts in a transverse direction. This makes play in the connection between the anchor parts in this direction, so that relative expansion and contraction may take place without setting up undesirable stresses in the wall or lining.

The upturned end 13 of the part 10 with the slot or opening in the part 14 provides a quick detachable connection between these parts. They are adapted to be conveniently disconnected for handling and installation. 55 The parts 10 may all be secured in the brick wall 21 first, and the parts 14 may be conveniently connected or applied thereto as the lining 24 is run up.

Owing to the slidable relation between the parts 10 and 14, the vertical positions of the parts 14 with respect to the parts 10 may vary. Ample vertical movement of the parts 14 relative to the parts 10 is permitted without the parts becoming disengaged and without the bases 11 and 15 coming into contact. It is not, therefore, necessary to bring the lining to an exact height each time before applying the part 14, and by securing the parts 10 in the wall 21 first and applying the parts 14 as the lining is laid or run up, the parts 14 will not interfere with the laying of the lining 24.

As will be seen from Figure 2, the tie 10 is placed about one of the bricks 20 in the retaining wall 21 and is anchored between two courses of bricks, as by embedding it in the mortar 22 between the courses. The dimensions of the tie are such that one of the ends will project out into the lining to engage the anchor part 14. To assure play at the connection between the anchor parts 10 and 14, and to prevent the plastic lining 24 from interfering with this play, wet paper, asbestos, or any other suitable material 23 may be loosely packed about the joint or connection, and the plastic lining 24 then built around it. As many anchors as desired may be used to hold the lining 24, adjacent lining wall 25 in place.

90 The upturned end 12 holds the part 10 firmly against displacement from the courses between which it is anchored. The length of the base 11 is preferably longer than the dimension of that part of the brick along which it extends, so as to space the end or tongue 13 from the surface of the wall 21 sufficiently to receive the slotted end of the part 14. The end 17 and the oppositely turned tongue 19 may cooperate with opposite sides of the 100

end or tongue 13, and the upturned end 16 of the part 14 anchors the lining to the wall and against separation therefrom.

The slot 18 is preferably of a width to 5 receive the tongue 13 without permitting appreciable relative movement between the anchor parts in a direction intersecting the plane of the surface of the wall 21.

After being laid up with the anchors in 10 stalled the plastic lining may be then dried by a slow fire and subsequently hardened by raising the temperature. Should the temperature tend to melt or burn out the anchors, the lining will be amply strong enough 15 to support itself by that time.

It is then apparent that I have provided a means for anchoring the plastic lining to the retaining wall, which will permit play between the parts and relative motion of translation 20 between them in different directions parallel to the engaging faces of the lining and wall. This permits the expansion and contraction of the lining during the drying and hardening process without producing 25 undesirable stresses therein.

I claim:

1. In a furnace, a retaining wall, a lining therefor, and anchor means holding the lining to the wall, said anchor means being adapted to permit expansion and contraction of the lining independently of the wall.

2. In a furnace, a retaining wall, a lining, and an anchor holding the lining to the wall, said anchor comprising two members 35 embedded in the lining and the wall, respectively, and connected by a joint adapted to permit relative movement between said members substantially parallel to the wall.

3. In a furnace, a retaining wall, a lining 40 of originally plastic material for said wall, and means for holding said lining to said wall, said means comprising an element secured to said wall and an element lodged in said lining against withdrawal therefrom, 45 said elements being joined against separation in direction transversely of the adjacent faces of said wall and lining and relatively movable in all directions parallel to said faces, whereby expansion and contraction of 50 said lining independently of said wall is permitted.

4. An anchor for holding a lining of originally plastic material to the wall of a furnace comprising an element for securing to said wall and an element for lodging in said lining against withdrawal therefrom, said elements being joined against separation in one direction and relatively movable in all directions in a plane normal to said first-named direction, whereby independent expansion and contraction of the wall and lining to which said anchor is applied may be permitted.

5. Means for anchoring plastic linings to furnace walls constructed wholly of masonry,

and originally lined with fire brick or a similar refractory, comprising in combination, a member adapted to be secured to a furnace wall, a second member adapted to be embedded in a plastic lining for said wall and 70 means for connecting said members together whereby the plastic lining is maintained in close proximity to the furnace walls but is permitted to move in expanding and contracting through short distances in directions parallel to the wall without cracking or bulging, said anchored member being a plate adapted for easy embedding in the masonry. 75

6. Means for anchoring linings to furnace walls constructed wholly of masonry, comprising in combination, a member adapted to be secured to a furnace wall, a second member adapted to be embedded in a plastic lining for said wall and means for connecting said members together whereby the plastic 80 lining is maintained in close proximity to the furnace walls but is permitted to move in expanding and contracting through short distances in directions parallel to the wall without cracking or bulging, said anchored 85 member being a plate adapted for easy embedding in the masonry during or after construction of wall.

7. Means for anchoring linings to furnace walls constructed of masonry comprising, in 90 combination, a member adapted to be secured to the furnace wall by the emplacement of a portion thereof within a masonry joint so as to lie within the wall and substantially parallel to the adjacent faces of the wall and lining, a second member adapted to be embedded in a plastic lining for said wall, and means for connecting said members together whereby the plastic lining is maintained in close 95 proximity to the furnace walls but is permitted to move, in expanding and contracting, through short distances in directions parallel to the wall without cracking or bulging. 100

8. In a furnace, a retaining wall, a monolithic lining, a tie member anchored in said retaining wall, an anchor member embedded in said lining, and a tongue and slot connection between the inner end of the tie member and the outer end of the anchor member, the slot of said connection being unobstructed and disposed in substantial parallelism with the inner face of the retaining wall. 110

9. In anchoring means of the character described, a U-shaped member having a 120 transverse slot through its bight portion and adjacent one arm, and a second U-shaped member having a relatively narrow arm projecting through said slot.

10. A wall and lining anchor comprising 125 a channel shaped part adapted to be anchored between courses of a brick wall and having an upstanding tongue spaced from the surface of the brick wall and disposed in the lining, a second part having a slotted end slidingly 130

mounted upon the tongue of said first part and adapted for lateral movement relative thereto, and a tongue at the opposite end of said second part turned out of the plane thereof and embedded in the lining.

5 11. In a furnace, a brick retaining wall, a monolithic lining, and means for holding said lining in place comprising a tie member partially surrounding one of the bricks in said wall and projecting into said lining, an anchor member embedded in said lining, and unobstructed tongue and slot means connecting the tie and anchor members, said means preventing movement between the tie and anchor members in a direction intersecting the adjacent faces of the wall and lining and permitting relative transverse movement between the tie and anchor members.

10 12. In a furnace, a brick retaining wall, a monolithic lining, a tie member partially surrounding a brick in said retaining wall and having a portion extending into said lining, and an anchor member embedded in said lining and having an elongated aperture to engage the extending portion of said tie member.

15 13. In a construction of the character described, a wall, a lining therefor, an anchor member secured in the wall and projecting beyond the inner face of the wall into the lining, said anchor member being provided at its inner end with a straight arm disposed substantially parallel to the inner face of the wall, and an anchor member secured in the lining and having a slot of relatively great length receiving said arm, the connection between the arm and the second anchor member being unobstructed by the lining permitting free movement of the second anchor member lengthwise of the arm and lengthwise of the slot accommodating expansion and contraction of said lining in all directions in its plane, the lining being otherwise unsecured to the wall.

20 14. In a furnace, a retaining wall, a lining, and an anchor for holding said lining to said wall said anchor comprising two members embedded in the lining and the wall, respectively, and connected by a joint adapted to permit relative movement between said members substantially parallel to the wall, and a packing about said joint to prevent said joint from becoming clogged and comprising a quantity of loose fibrous material.

25 55. In witness whereof, I hereunto subscribe my name this 9th day of July, 1926.

IVON S. PIETERS.
